Primary Examiner — Karen S Acker(74) *Attorney, Agent, or Firm* — Brinks Hofer Gilson & Lione(57) **CLAIM**

We claim the ornamental design for a perforated stripping with header, as shown and described.

DESCRIPTION

FIG. 1 is a front elevation view of a perforated stripping with header.

FIG. 2 is a side view of the design of FIG. 1, the opposite side being a mirror image; and,

FIG. 3 is top plan view of the design shown in FIG. 1. The broken line in FIGS. 1 and 2 indicates the boundary of the perforated stripping with header and forms no part thereof.
